UNITED STATES PATENT OFFICE.

WALTER J. MAINTHOW, OF NEW YORK, N. Y.

GARMENT.

1,338,187.

Specification of Letters Patent. Patented Apr. 27, 1920.

Application filed May 5, 1919. Serial No. 294,855.

To all whom it may concern:

Be it known that I, WALTER J. MAINTHOW, a citizen of the United States, and resident of New York, county of New York, 5 and State of New York, have invented certain new and useful Improvements in Garments, of which the following is a specification.

My invention relates to garments and 10 more particularly to infants' garments and has for its object to provide a garment including a collar which may be readily converted into an attractive hood or cap at will. Other more specific objects of my invention 15 will appear from the description hereinafter and the features of novelty will be pointed out in the appended claims.

In the accompanying drawings, which, for 20 illustrative and descriptive purposes, show an example of my invention, Figure 1 is a front view showing the collar converted into a hood or cap; Fig. 2 is a side view of Fig. 1; and Figs. 3 and 4 are views illustrating the collar in upwardly extended positions 25 prior to its conversion into a hood or cap; and Fig. 5 is a detail view showing another arrangement of fastening devices.

The garment may comprise a body portion 5 of any type or style and may include 30 sleeves 6 and the usual fastening devices 7 whereby the garment is closed. As illustrated, the garment further includes the collar 8 which is fastened to the neck band in the usual way and extends around the same 35 to the front of the garment where it terminates near the front opening thereof along lines which diverge from said neck-band as shown at 9 in Fig. 3. The collar 8 extends over the shoulders and is continued to 40 form a rear portion 10, the outer edges 11 of which diverge to the transverse lower edge 12 and which presents the appearance of that type of collar commonly termed "sailor collars." In the illustrated example, 45 the collar is provided with button holes 13, a row of which extends along each longitudinal outer edge 11 from points near the edge 12 toward the neck band of the garment to intermediate points of said edges 11. But-

50 tons 14 are arranged in rows which extend substantially along the longitudinal outer edges 11 from points near the terminal button hole 13 in each button hole row, inwardly and terminate near the junction of the 55 front edges 9 with the neck band, said rows of buttons 14, in other words, constituting con-

tinuations of the rows of button holes 13, as shown in Fig. 3. An additional button 15 may be located on each side of the collar in the angles formed by the outer edges 11 and 60 the front edges 9. The buttons 14 and 15 are located on the underside of the collar when the latter is in its normal position and are thus invisible and do not detract from the appearance of the collar as such. It 65 will, of course, be understood that the buttons and button holes may be replaced by equivalent fastening devices of other types and that I intend to include such equivalent fastening devices wherever I use the 70 terms "buttons" and "button holes." For instance, as shown in Fig. 5, the button 14 may be replaced by loops 14^a and the button holes 13 replaced by buttons 13^a with which said loops 14^a coöperate to fasten the 75 collar in the form of a hood. With this arrangement the loops 14^a and buttons 13^a are all located on the inside of the collar and thus are invisible when the latter is worn in its normal position. 80

To convert the collar into a cap or hood, the outer edges 11 of the collar are turned over and inward from the front edges 9 to a point near the intermediate terminal button hole 13, thus forming flaps 16, as shown 85 in Fig. 4. The rows of buttons 14 in this condition are exposed and extend substantially along the outer edges defined by the flaps 16. The rear portion 10 of the collar 8 is now folded over along an imaginary 90 line 17 which extends transversely to the length of the collar and between the apices of the flaps 16, so as to extend over the latter which brings the button holes 13 into registry with the buttons 14. This brings 95 the collar into the form of an attractive hood in which condition it may be retained by connecting the buttons 14 and button holes 13 in the usual way. If a larger size hood is desired, one of each row of button holes 13 may be connected with the buttons 15; in this case it may be necessary to disconnect one or more additional buttons 14 and button holes 13 in order to secure the 100 desired result. 105

When the collar is arranged as a hood or cap, the two rows of buttons 14 are visible and extend along the opposite sides of the head in a manner which gives the hood or cap a shape closely simulating that of a real 110 hood or cap, as shown in Fig. 2; in addition, the rows of buttons present an ornamental

appearance and add to the attractiveness of the garment.

A garment provided with my convertible collar may be efficiently utilized as a sleeping garment, and other garments intended for specific uses, it being obvious that the arrangement may be used equally well in dress garments of any description and in any case provides an efficient hood or cap 10 which is available for use wherever and whenever required.

I am aware that garments have heretofore been provided with collars convertible into head coverings, such collars, however, having either the form of a hood even when worn as a collar or otherwise being simply folded and secured over the head and providing merely a covering for the head without attractiveness as a hood. I am aware 20 also that buttons have been placed along one edge of a collar for coöperation with button holes located along the opposite edge of said collar whereby the latter is secured after being folded over the head, as shown, for 25 instance, in the Patent No. 1,131,674 of March 16, 1915, to William M. Buckley. I believe myself to be the first, however, to provide a collar having buttons and button holes or equivalent means along both longitudinal outer edges of a collar so arranged 30 that the button holes and buttons of each edge coöperate to convert the collar into an actual hood or cap of attractive and ornamental appearance and of maximum efficiency as a head covering.

While the invention has been illustrated as a part of a garment including sleeves, it will be understood that my improved convertible collar is capable of efficient combination with other types of garments, including such as are commonly known as capes. Further, while the invention is particularly adapted for use in infants' garments of all kinds, it is not restricted to such use and 45 may be advantageously incorporated in garments intended for use by children and adults.

Various changes in the specific form shown and described may be made within 50 the scope of the claims without departing from the spirit of my invention.

I claim:

1. In a garment, a convertible collar arranged to be folded forwardly upon itself 55 along a line transverse to the length of the collar to divide its outer edges into two sections in registry with each other and coöp-

erating fastening devices whereby said two sections are detachably connected at said outer edges to form a hood.

2. In a garment, a convertible collar, a row of fastening devices extending along each longitudinal outer edge of said collar from the transverse edge thereof to an intermediate point of said outer edge and a 60 row of coöperating fastening devices extending along each longitudinal outer edge of said collar and forming continuations of each row of said first-mentioned fastening devices toward the neck band, said collar being foldable forwardly along a line transverse to the length of the collar to bring the operating fastening devices of each row into registry and connection with each other to convert said collar into a hood.

3. In a garment, a convertible collar having its longitudinal outer edges turned inwardly to form flaps extending from intermediate points of said outer edges toward the neck band of the garment, said collar being folded forwardly upon itself along a line transverse to the length of the collar so as to lie over and extend between said flaps and coöperating fastening devices on said flaps and the overlapping contiguous portions of said collar for connecting said flaps and collar portions together to form a hood.

4. In a garment, a convertible collar, a row of fastening devices extending along each longitudinal outer edge of said collar 90 from the transverse edge thereof to an intermediate point of said outer edge and a row of coöperating fastening devices extending along each longitudinal outer edge of said collar on the reverse side thereof and forming continuations of each row of first mentioned fastening devices toward the neck band, said collar being foldable inwardly at its longitudinal outer edges to form flaps extending from intermediate points of the 95 outer edges toward said neck band and to bring each row of coöperating fastening devices into operative positions, that portion of said collar which is beyond said flaps being foldable forwardly along a line transverse to the length of the collar so as to lie over and extend between said flaps and to bring the fastening devices of each row into 100 registry and connection with each other to convert said collar into a hood.

In testimony whereof I have hereunto set my hand.

WALTER J. MAINTHOW.
